(57) **CLAIM**

The ornamental design for plush sunglasses, as shown.

DESCRIPTION

An article embodying the design as shown in the present application is in the nature of sunglasses having a soft, plush makinal on all surfaces except the lenses. This article is particularly intended for use by infants and toddlers.

FIG. 1 presents an elevated perspective view of the plush sunglasses of the present invention.

FIG. 2 presents a side view of the plush sunglasses of the present invention. The other side view is identical to this view; and,

FIG. 3 presents a top view of the plush sunglasses of the present invention. The bottom view is identical to this view.
